UNITED STATES PATENT OFFICE.

DAVID H. ZELL, OF NEW YORK, N. Y.

DESIGN FOR A VANITY CASE.

Application filed January 27, 1928. Serial No. 25,059. Term of patent 7 years.

To all whom it may concern:

Be it known that I, DAVID H. ZELL, a citizen of the United States, residing at New York, in the county of New York and State of New York, have invented a new, original, and ornamental Design for Vanity Cases, of which the following is a specification, reference being had to the accompanying drawing, forming part thereof.

The drawing is a perspective view of a vanity case showing my new design.

The dominant feature of the design resides in the particular type of ornamentation as shown on the front or cover of the vanity case.

In the illustrated example of my invention, the opposite side of the case is unornamented.

I claim:

The ornamental design for a vanity case as shown and described.

DAVID H. ZELL.
